DRILL STEM

Frank Miller, Easton, Pa., assignor to Ingersoll-Rand Company, Jersey City, N. J., a corporation of New Jersey

Application August 7, 1935, Serial No. 35,069

6 Claims. (Cl. 255—28)

This invention relates to drilling devices, and more particularly to a drilling device adapted to be actuated by a rotary drilling rig.

One object of the invention is to enable the drilling of holes by means of a rotary drilling rig without necessitating frequent interruptions in the drilling operation for lengthening the drill rod whereby rotary motion is transmitted from the drilling rig to the cutting implement.

Another object is to enable the drill rod, whereby rotary movement is transmitted from the drilling rig to the working implement, to automatically extend itself in accordance with the degree of penetration of the working implement into the work.

Other objects will be in part obvious and in part pointed out hereinafter.

In the drawings accompanying this specification and in which similar reference numerals refer to similar parts,

Figure 1 is an elevation, in section, of a drilling device constructed in accordance with the practice of the invention.

Figure 2 is a perspective view in elevation, partly broken away, of a portion of the drilling device.

Figure 3 is a transverse view taken through Figure 1 on the line 3—3, and

Figure 4 is a view similar to Figure 1 showing a modified form of the invention.

Referring more particularly to the drawings, and at first to Figures 1 to 3 inclusive, 20 designates a portion of a drilling rig illustrated as being of the rotary type, and 21 designates a drilling device constructed in accordance with the practice of the invention and interlockingly engaging the drilling rig 20.

The drilling device 21 comprises a plurality of rod sections 22, 23 and 24 of progressively decreasing cross section in the order named and adapted to be nested one within the other and freely slidably with respect to each other. In the drawings three rod sections are shown, although any suitable number of rods may be employed depending upon the distance which it is desired to penetrate the work or upon the length of the several sections. The rod sections are shown as being of rectangular shape and in the form of the invention illustrated the rod 22, which constitutes the outermost section, is interlocked slidably with the drilling rig 20 so that, upon rotation of the driver 25 of the drilling rig, the rod 22 will rotate therewith.

The rod 23 extends slidably into the rod 22 and is interlockingly connected therewith. The inner surface 26 of the rod 22 serves as a guiding

surface for the rod 23 or, more particularly, for a flange 27 at the rear extremity and outer surface of the rod 23. The flange 27 may be an integral portion of the rod 23 or constitute a separate element which may be secured to the rod, as for instance by welding. Thus, in the assembled positions of the rods the outer surface of the flange 27 will be in slidable engagement with the inner surface 26 of the rod 22 and the two rods will, therefore, be held against relative rotary movement but will be capable of free slidable movement with respect to each other.

Additional guiding means are provided for the rod 23 in the form of a flange 28 in the front end of the rod 22. The interior of the flange 28 defines a guiding surface 29 for the rod 23 which may slide freely through the flange 28 and interlockingly engages said flange to prevent relative rotary movement between the rods 22 and 23.

In order to limit the distance which the rod 22 may descend with respect to the drilling rig 20 the rod 22 is provided with an external shoulder 30 adjacent its rear end to seat upon the driver 25 and thus prevent the rod 22 from sliding out of engagement with the drilling rig.

In the essential respects the rod 23 is a substantial duplicate of the rod 22. It differs therefrom principally in that it is of smaller cross sectional area. In other words, the rod 23 is provided at its forward end with an internal flange 31 defining a rectangular opening 32 to slidably engage and serve as a guide for the innermost rod 24. The flange 31, moreover, serves as an abutment for an external flange 33 on the rear end of the rod 24 to prevent removal of the rod 24 from the rod 23. The outer surface of the flange 33 is slidably interlocked with the internal surface of the rod 23 and thus, as will be apparent, a substantial area of interlocking engagement will be maintained between the rods 24 and 23 to assure the transmission of rotary movement from one rod to another.

Secured to the lowermost end of the rod 24 is a chuck 34 which may be split longitudinally to provide a pair of half-sections 35. The sections 35 have longitudinally extending flanges 36 which, in the assembled position of the sections, lie in face to face relationship and are clamped together by means of bolts 37 extending therethrough. The rearward portion of the sections 35 are recessed to provide a rectangular bore 38 corresponding to the shape of the rod 24 which extends into the bore. In order to prevent endwise movement of the chuck with respect to the rod 24 these elements are preferably provided

with interlocking portions, as for example a rib 39 on the chuck and a groove 40 in the outer surface of the rod 24.

On the lowermost end of the chuck 34 is a lateral flange 41 which serves as a seat for a cutting implement 42 secured to the flange by means of bolts 43. The cutting implement may be of any suitable type adapted for cutting rock, and in the rearward surface of the cutting implement is a recess 44 to receive a boss 45 on the adjacent surface of the chuck 34 for centralizing the two with respect to each other. The recess 44 and the boss 45 are preferably also of polygonal shape in order to form interlocking portions between the two transmitting rotary motion from the chuck to the working implement.

To the end that the drilling device, including the rods 22, 23, 24, the chuck and the working implement may be removed from the drill hole as a comparatively short unit, means are provided to move the rods telescopically into each other and thus shorten the assembly prior to its removal from the hole being drilled. To this end a pipe 46 is extended through the rods and the chuck 34 and terminates with its lower end within a recess 47 in the chuck.

On the portion of the pipe lying within the recess 47 is a collar 48 which may be suitably affixed to the pipe 46 and seats against an anti-friction thrust bearing 49 in the chuck 34. In drilling operations where it is essential to provide a clean working surface for the cutting implement, as when drilling rock, the pipe 46 may also serve to convey cleansing liquid to the bottom of the hole being drilled. In such case the chuck 34 and the working implement are provided with passages 50 and 51, respectively, which register with each other and with the interior of the pipe 46 for that purpose.

The operation of the device is as follows: After the rods 22, 23 and 24 are placed in position in the driver 25 of the drilling ring so that the rod 22 will be interlockingly engaged therewith, the chuck 34 with the attached working implement is connected to the rod 24. The drilling rig is then set in operation to drill the hole and as the working implement penetrates the work the rods will gradually descend through the driver 25, and, at first in unison, until a hole of sufficient depth has been drilled to permit the shoulder 30 to seat against the driver 25.

From this point on only the rods 23 and 24 will descend until the flange 27 abuts the flange 55 28 and prevents further descending movement of the rod 23. Thereafter, only the rod 24, the chuck and the working implement will descend into the work. This movement of these elements may continue until a hole of the desired depth 60 has been drilled or until the shoulder 30 of the rod 24 contacts with the flange 31.

During this operation, and in the event that the working implement has been employed for cutting rock, water under pressure may be introduced through the pipe 46 and the passages 50 and 51 to the drill hole to flush the cuttings therefrom. After the drill hole has been completed lifting force is applied to the pipe 46 and the working implement and the rod 24 are lifted 70 until the chuck engages the front end of the rod 23. The rod 23 will then also be carried upwardly into the rod 22 and when the front end of the rod 22 engages the chuck 34 the rod 22 will also be carried upwardly until the working implement has been removed from the drill

hole. The chuck 34 may then be removed from the rod 24 and the rods be withdrawn from the driver 25 preparatory to moving the drilling apparatus to another site.

As will be readily apparent to those skilled in the art, by employing a plurality of rod sections in which adjacent sections are in slidably and interlocking engagement with each other a preassembled rod capable of effecting the drilling of a comparatively deep hole may be employed in locations having low head room. This form of construction, moreover, eliminates the necessity of frequent prolonged idle periods of the drilling apparatus in order to add extensions to the drill rod as is customary in apparatus in which the rod sections are threadedly connected together. Thus, when the innermost rods are withdrawn into the outer rod 22 a preassembled drilling rod capable of drilling a deep hole will initially require only the head room of the outermost rod. Moreover, after the hole has been completed the unit may be expeditiously removed from the drill hole by merely applying lifting force to the pipe 46.

The form of the invention illustrated in Figure 4 is more particularly adapted for drilling top soil overlying a rock bed, that is, for such forms of drilling in which it is not essential nor desirable to flush the loosened material from the hole being drilled. The chuck designated 52 secured to the lowermost end of the rod 24 is accordingly threaded, as at 53, for the accommodation of a threaded shank of an earth auger 54 whereby the soil is loosened and elevated to the surface. As in the form of the invention previously described the chuck 52 is provided with an anti-friction thrust bearing 49 against which seats a collar 55 secured to the end of a flexible member 56 illustrated as a cable and extending through the rods connecting the chuck with the drilling rig. The cable 56, like the pipe 46, serves as a means for retracting the rods, the chuck and the auger 54 from the hole being drilled and, as will be readily understood, by seating the collars carried by the pipe 46 and the cable 56 against a thrust bearing the rotary motion of the chuck will not be transmitted to the cable or the pipe.

I claim:

1. A drilling device, comprising a plurality of rods nested one within the other and being freely slidable with respect to each other, means for preventing rotary movement of one rod with respect to another rod, a working implement carried by the innermost rod, and means for moving the rods into telescopic relationship with each other and to convey cleansing fluid to the working implement.

2. A drilling device, comprising a rotary rod, a second rod within and slidably interlocked with the first said rod, a working implement carried by the second mentioned rod, means extending through the rods for moving the second mentioned rod into the first mentioned rod and for conveying cleansing fluid to the working implement, and means for preventing the transmission of rotary movement from the rods to the first mentioned means.

3. A drilling device, comprising a plurality of rotary rods nested one within the other and being freely slidable with respect to each other, said rods having interlocking portions to prevent relative rotary movement between the rods, a chuck on the innermost rod to accommodate a working implement, an anti-friction bearing in

the chuck, and means extending through the rods for conveying cleansing fluid to the working implement and acting against the anti-friction bearing for drawing one rod into another.

- 5 4. A drilling device, comprising a plurality of rotary rods nested one within the other and being freely slideable with respect to each other, said rods having interlocking portions to prevent relative rotary movement between the rods, a 10 chuck on the innermost rod to accommodate a working implement, an anti-friction bearing in the chuck, a conduit within the rods for drawing one rod into another and to convey cleansing fluid to such working implement, and means on 15 the rod seating against the anti-friction bearing to prevent the transmission of rotary movement from the rods to the conduit.
5. A drilling device comprising a plurality of rods arranged in telescopic fashion and having

interlocking portions to prevent relative rotary movement between the rods, said rods having external collars at only their uppermost ends and said rods, with the exception of the innermost rod, having internal collars at only their lowermost ends, and a working implement carried by the innermost rod.

6. A drilling device comprising a plurality of rods arranged in telescopic fashion and having interlocking portions to prevent relative rotary 10 movement between the rods, a working implement carried by the innermost rod, said rods having external collars at only their uppermost ends and said rods, with the exception of the innermost rod, having internal collars at only 15 their lowermost ends, and means for lifting the working implement and for moving one rod into another.

FRANK MILLER.
